J. DERRY

TOGGLE PRESS

Filed July 10, 1924

INVENTOR:

Jasper Derry.
By Machinist, Calver, Copeland & Dyer.

ATTORNEYS-

UNITED STATES PATENT OFFICE.

JASPER DERRY, OF MEDFORD, MASSACHUSETTS, ASSIGNOR TO ANDREW TERKELSEN,
OF BOSTON, MASSACHUSETTS.

TOGGLE PRESS.

Application filed July 10, 1924. Serial No. 725,310.

This invention relates to toggle presses of the type shown and described in my prior application filed February 18, 1924, Serial No. 693,478, and wherein mechanical means, 5 preferably in the form of compression springs, are employed to exert a follow-up pressure on the ram after the toggle is straightened.

The present invention has for its objects 10 to provide, in a press of this type, means whereby the follow-up pressure can be adjusted, and also to provide means for measuring and indicating the amount of such pressure.

15 The more particular objects of the invention, together with means whereby the latter may be carried into effect, will best be understood from the following description of one form or embodiment thereof illustrated in 20 the accompanying drawings. It will be understood, however, that the particular construction described and shown has been chosen for illustrative purposes merely, and that the invention, as defined by the claims 25 hereunto appended, may be otherwise embodied without departure from the spirit and scope thereof.

In said drawings:

30 Figs. 1 and 2 are a side and a front elevation respectively of a toggle press embodying the invention.

Fig. 3 is a section taken substantially on the line 3—3, Fig. 2.

As shown, the frame of the press comprises 35 a pair of side uprights 10 supporting four upright posts 12 which in turn support, through adjustable nuts 14, the bed plate 15 which carries the bed or stationary element of the press 16. The ram or co-operating 40 movable element 17 is guided on the posts 12 and is operated by a toggle 18 interposed between said ram and a cross-head 19 slidably mounted on the posts 12 and normally supported by fixed collars or nuts 20 on said 45 posts. The toggle 18 is straightened or broken to depress or lift the ram by means of a link 21 having rollers 22 co-operating with a cam 23 on a shaft 24 journalled in the uprights 10. The shaft 24 is rotated, through 50 gearing generally indicated at 25, and under the control of a suitable clutch 26, from a main power shaft 27 also journalled in the uprights 10 and adapted to receive power from any suitable source. The specific form 55 of the particular driving connections is im-

material, and these may be of any suitable arrangement well known in the art.

In accordance with the present invention, the posts 12 are threaded at their upper ends to receive nuts 28 which may be adjusted 60 upon said posts and may be secured in adjusted position by lock nuts 29. The nuts 28 constitute adjustable abutments between which and the cross-head 19 are interposed spiral springs 31 surrounding the posts. In 65 the construction shown, washers 40 are interposed between the upper ends of the two rear springs 31 and the adjacent nuts 28, while in a corresponding position at the front there is provided an auxiliary cross-head 30 70 guided at its ends on the two forward posts 12.

As in my prior application above referred to, the springs 31 are collectively of a strength sufficient to transmit, without 75 yielding, forces less than the maximum pressure to be exerted by the press but to yield when said pressure is reached. The strength of said springs, and consequently the forces transmitted thereby without yielding, is determined by the initial compression to which 80 said springs are subjected, and this pressure can, in accordance with the present invention, be readily varied by adjustment of the nuts 28. In order that this pressure may be 85 readily measured and indicated, the cross-head 19 is provided with a graduated dial 32 with which co-operates a pointer 33 carried by a pinion 34 rotatably mounted on 90 said cross-head and co-operating with a rack 35 depending from the auxiliary cross-head 30. The rack 35 is preferably adjustably connected with the auxiliary cross-head 30 by means of nuts 36 on the threaded stem of 95 said rack which extends through an opening in said cross-head, the adjustment of the nuts 36 serving to calibrate the indicator. It will thus be seen that the relative movement of the cross-heads 19 and 30 incidental to compression or expansion of the springs 100 31 will be indicated by the pointer 33 on the dial 32.

The operation of the press above described is substantially as explained in my prior application above referred to. The bed plate 105 15 is so adjusted, in accordance with the dies (not shown) and the size of the work, that the latter is subjected to its maximum pressure by the ram 17 just prior to the straightening of the toggle 18 by the cam 110 23.

23. When said maximum pressure is reached, the springs 31 yield, permitting said toggle to be completely straightened. The maximum pressure on the work is thereby maintained by said springs, and after the material contracts, said springs expand to exert a follow-up pressure thereon. The extent of the pressure is determined by the initial adjustment of the nuts 28 and is indicated by the pointer 33 on the dial 32, the variations in pressure incidental to the operation of the ram and the subsequent contraction of the material being readily followed by the operator by observation of the indicator.

Having thus described my invention, I claim:

1. In a press, in combination, a ram, a toggle for operating said ram, means for straightening said toggle, mechanical means for exerting a follow up pressure upon said ram after said toggle is straightened, and means for measuring and indicating the amount of said pressure.

25 2. In a press, in combination, a ram, an adjustable abutment, a toggle interposed between said ram and abutment, a spring through which said toggle reacts upon said abutment, means for measuring and indicating the tension of said spring, and means for straightening said toggle.

30 3. In a press, in combination, an abutment, a movable head, a spring interposed between said abutment and head, a ram, a toggle interposed between said ram and head, means for straightening said toggle, and means for measuring and indicating the

relative movement of said abutment and head.

4. In a press, in combination, an adjustable abutment, a movable head, a spring interposed between said abutment and head, a ram, a toggle interposed between said ram and head, means for straightening said toggle, and means for measuring and indicating the relative movement of said abutment and head.

45 5. In a press, in combination, frame members having abutments, a ram guided by said frame members, cross-heads guided by said frame members, one of said cross-heads engaging said abutments, a toggle interposed between the other of said cross-heads and said ram, means for straightening said toggle, springs interposed between said cross-heads, a rack carried by one of said cross-heads, a pinion carried by the other of said cross-heads and cooperating with said rack, and an indicator operated by said pinion.

50 6. In a press, in combination, frame members having adjustable abutments, a ram guided by said frame members, cross-heads guided by said frame members, one of said cross-heads engaging said abutments, a toggle interposed between the other of said cross-heads and said ram, means for straightening said toggle, springs interposed between said cross-heads, a rack carried by one of said cross-heads, a pinion carried by the other of said cross-heads and cooperating with said rack, and an indicator operated by 55 said pinion.

In testimony whereof I affix my signature.

JASPER DERRY.
